UNITED STATES PATENT OFFICE.

BERT H. RHODES, OF SEATTLE, WASHINGTON.

DESIGN FOR A TRANSPARENT SIGN.

50,030.

Specification for Design.

Patented Dec. 12, 1916.

Application filed December 22, 1915. Serial No. 68,269. Term of patent 3½ years.

To all whom it may concern:

Be it known that I, BERT H. RHODES, a citizen of the United States, and a resident of Seattle, in the county of King and State of Washington, have invented a certain new, original, and ornamental Design for a Transparent Sign, of which the following is a specification, reference being had to the

accompanying drawings, forming part thereof.

The figure illustrates the design of my transparent sign.

I claim:

The ornamental design for a transparent sign, as shown.

BERT H. RHODES.
